INVENTOR
Charles Betz.
By *George Koenig*
ATTORNEY

UNITED STATES PATENT OFFICE.

CHARLES BETZ, OF ST. LOUIS, MISSOURI.

MATERIAL-FASTENING DEVICE.

Application filed February 11, 1926. Serial No. 87,564.

This invention relates generally to fastening devices and, more particularly, to a certain new and useful device adapted especially for securing or fastening material, such as "beaver board," linoleum, and other such sections or the like, to studding or other frame-work in the formation of walls and partitions, to flooring, or upon other surfaces or supports.

10 My present invention has for its chief object the provision of means in the form preferably of suitably elongated metallic strips of simple and inexpensive form and construction which may be readily secured or otherwise fixed to the studding, flooring, or other surface or support and by which panels or sections, such as, for instance, sections or strips of beaver-board, linoleum or the like, may be conveniently, quickly, and 20 efficiently secured and held in place and the joints or seams therebetween concealed.

And with the above and other objects in view, my invention resides in the novel features of form, construction, arrangement, 25 and combination of parts hereinafter described and pointed out in the claims.

In the accompanying drawings,—

Figures 1 and 2 show in perspective and in preferred form co-operative fragments of 30 material-securing and joint-concealing devices or strips embodying my invention;

Figure 3 shows in section a fragment of a wall-studding, a pair of wall-boards, and fastening means of preferred form of my invention, the latter being disposed with relation to the studding and boards preparatory to final securing of the boards;

Figure 4 is a view similar to Figure 3, with the boards and fastening means in final 40 board-securing and joint-concealing position;

Figure 5 is a view similar to Figure 3, illustrating, however, a slightly modified form of material fastening means embodying my invention; and

Figure 6 is a view similar to Figure 5, with the boards and fastening means in final board-securing and joint-concealing position.

50 Referring now more in detail and by reference characters to the drawing, A designates the so-called clinchable member and B the so-called material-engaging member of the preferred form of my new fastening device.

The member A is constructed of suitable

bendable sheet metal, is normally approximately of C-shape in end view and section, as best seen in Figures 1 and 3, and integrally includes a generally flat base wall 1, 60 rounded or arcuated side-walls 2, 2, and in-turned flanges 3, 3, suitably spaced from and disposed in overhanging relation to base-wall 1 and also suitably spaced from each other at their free margins. Lengthwise 65 and approximately centrally between the side walls 2, base wall 1 is provided with a series of spaced nail-accommodating perforations or openings 4.

The member B is also constructed of suitable bendable sheet metal, is normally approximately of T-shape in end view and section, as seen in Figures 1 and 3, and includes, the material of which it is composed being doubled upon itself, a double-wall rib 75 or web 5 and double-wall oppositely disposed flanges 6, 6, presented outwardly from an end of and at an angle to the web 5, the wall-members of rib or web 5 at their lower free margins having extensions 7, 7, separated or spaced and bent to oppositely and arcuately flare outwardly, as shown, and the flanges 6 being downwardly pronged, as at 8, 8, lengthwise along their outer margin.

It will be understood that the members A 85 and B are formed by rolling or other suitable operations in suitable sizes and dimensions and cut to lengths as required.

For purposes of illustration, I here show my new fastening strips in wall-forming connection, and to such end C designates an intermediate studding or post of a building wall or partition, and D, D, designate panels or sections of wall-forming material, such as, for instance, commercial "beaver 90 board", adapted for location and for securing upon the studding C to complete the wall or partition. As is common, the wall boards or sections D are uniformly pre-sized and are ordinarily of rectangular-oblong shape. Ordinarily, such wall-boards are butt-fitted over a frame element and secured by nailing through the boards into the frame element. Obviously, where headless nails are employed, the greatest precision 100 and skill must be exercised to avoid a grotesque arrangement of nail heads and obviously further where headless or "finish" nails are employed, the holding, at best, is insecure, even though a relatively great 105 number of nails is used. It is also quite common today that in the handling of the

wall-boards in commerce, much damage is done the margins—hence the ordinary wall or partition presents unsightly seams or joints between boards.

5 In the construction of a wall according to my present invention, a strip or member A is first lengthwise secured by nails or the like 9 flatwise at its base-wall 1 to and upon the studding C. The boards D are then 10 "butted" upon the studding C and over the secured or fixed strip or member A. A strip or member B is then disposed with its rib 5 intermediate the abutting ends of the boards D with its rib-extensions 7 resting 15 in the channel of strip A and with its flanges 6 overlapping upon the adjacent ends of the boards D. By means then of suitable pressure applied upon the member B through a hammer or other suitable tool 20 (not shown); the rib-extensions 7 are forcibly spread outwardly and clinched down upon the base-wall 1, the flanges 2 clinched downwardly upon and into impinging engagement with the so spread and clinched 25 rib-portions 7, and, at the same time, the ribs 6 embedded into engaging relation with the boards D. Thus the member B is securely fastened to the fixed strip A and, 30 through co-operative clinching engagement between the flanges 6 and the rib-extensions 7, the boards D to the studding C.

As shown in Figures 5 and 6, I may, as a modified form in the use of my new fastening strips, dispense with the strips or members A, slightly normally space the walls of the rib 5' and the walls of the flange 6' of the members B' and dispose the securing nails 9' with their heads and shanks intermediate the walls of the rib and flanges of 40 the strips B'. In the construction of a wall with strips of B' type, the strips B' are suitably disposed lengthwise upon, and partially by means of the nails 9' secured to, the studding C. The boards D are then fitted 45 upon the studding with their adjacent ends disposed under the flanges 6' and abutting approximately against the rib 5'. Under suitable pressure then applied upon the strips B', the rib-portions or extensions 7' 50 will be similarly spread and clinched directly upon the studding and the boards D at their edges will be clinched and securely held between the flanges 6 and the so spread and clinched rib-extensions 7', the nails 9' 55 at the same time being driven "home" and the strip firmly attached to the studding.

My new strips may be readily and inexpensively manufactured, and by the use of strips in accordance with my invention, I am 60 enabled to quickly, conveniently, tightly, securely, and efficiently bind and fasten wall-board, linoleum, and other such sections or the like in place and form a substantially seamless, smooth wall, partition, floor-covering, or the like, the margins of the several 65

sections being covered and the joints therebetween being concealed. I may add that the strips enable the wall, flooring, or the like, to more positively resist combustion, nails or other fastening means of the sections are concealed, and cracking of paper or other surfacing material at seams is obviated.

I am aware that changes in the form, construction, arrangement, and combination of the several parts of my new fastening strip may be made and substituted for those herein shown and described without departing from the nature and principle of my invention.

Having thus described my invention, what I claim and desire to secure by Letters Patent is:

1. Abutting material fastening and joint concealing means including a first sheet metal strip of C-shape in section adapted for disposition flatwise under the abutting material with its flanges presented upwardly and the opening therebetween in approximate alignment with the joint between said abutting material, and a second sheet metal strip of substantially T-shape comprising a web, oppositely disposed flanges presented outwardly from an end of and at an angle to the web, and oppositely disposed clinchable extensions projecting from the opposite end of the web, the second strip being adapted for disposition with its web between said abutting material, its flanges flatwise engaging the upper marginal edge-portions of said abutting material, and its said extensions projecting through the opening and beneath the flanges of the first strip, the two strips being adapted under pressure for interlocking engagement with the extensions of the second strip clinched by the flanges of the first strip, and said abutting material clinched directly between the flanges of the first and second strips.

2. Abutting material fastening and joint concealing means including a first sheet metal strip of C-shape in section adapted for disposition flatwise under the abutting material with its flanges presented upwardly and the opening therebetween in approximate alignment with the joint between said abutting material, a second sheet metal strip of substantially T-shape comprising a web, oppositely disposed flanges presented outwardly from an end of and at an angle to the web, and oppositely disposed clinchable extensions projecting from the opposite end of the web, the second strip being adapted for disposition with its web between said abutting material, its flanges flatwise engaging the upper marginal edge-portions of said abutting material, and its said extensions projecting through the opening and beneath the flanges of the first strip, the two strips being adapted under pressure for in-

terlocking engagement with the extensions of the second strip, and said abutting material clinched directly between the flanges of the first and second strips, and wall-engaging members projecting only through the first strip.

3. Abutting material fastening and joint concealing means including a strip comprising a double-wall web, oppositely disposed flanges presented outwardly from an end of and at an angle to the walls of the web, and

oppositely disposed extensions projecting from the opposite end of the walls of the web for clinchable co-operation with said flanges in engaging the abutting material, and a wall-engaging nail having the upper portion of its shank disposed between the walls of the web.

In testimony whereof I hereunto affix my signature.

CHARLES BETZ.
